UNITED STATES PATENT OFFICE.

EMMET L. SMITH, OF CHICAGO, ILLINOIS.

FRAMED PICTURE OR MIRROR HANGING DEVICE.

SPECIFICATION forming part of Letters Patent No. 730,055, dated June 2, 1903.

Application filed October 10, 1902. Serial No. 126,725. (No model.)

To all whom it may concern:

Be it known that I, EMMET L. SMITH, a citizen of the United States, and a resident of Chicago, in the county of Cook and State of Illinois, have invented a new and Improved 5 Framed Picture or Mirror Hanging Device, of which the following is a full, clear, and exact description.

This invention embodies a novel means for 10 attaching a flexible connection to a framed picture or mirror and a novel hook for the other end of said connection, whereby the frame may be conveniently and reliably hung from a fixed molding-strip.

15 The invention consists in the novel construction and combination of parts, as is hereinafter described, and defined in the appended claims.

Reference is to be had to the accompanying 20 drawings, forming a part of this specification, in which similar characters of reference indicate corresponding parts in all the figures.

Figure 1 is a side view of a hook engaged 25 with a molding-strip and embodying a feature of the improvements. Fig. 2 is a similar view, but showing a hook of different shape. Fig. 3 is a sectional side view of the hook represented in Fig. 2. Fig. 4 is a perspective view of the hook indicated in Figs. 2 and 3, representing more clearly a novel detail thereof, comprising a transversely-flattened end on the hook. Fig. 5 is a side view of a novel 30 cord attachment for the picture-frame. Fig. 6 is a side view of a cord attachment for a picture-frame, somewhat changed but generically similar to the device shown in Fig. 5. Fig. 6^a is a sectional side view of the device shown in Fig. 6. Fig. 7 is a side view of a modification of the cord attachment. Figs. 8 35 and 9 are side views of another modification of the cord attachment; and Fig. 10 represents a side wall in section, a molding-strip thereon, and the improvements applied for suspending a picture-frame from the molding-strip.

In the drawings, 10 indicates a molding-strip of ordinary form held in horizontal position on a side wall A and having the usual bead formation 10^a, projected forwardly at 45 the upper edge of said strip, and the valley

or depressed groove 10^b in the upper surface of the molding-strip near the wall A.

The improvements embody a novel hook for connecting one end of a flexible connection, that may be a wire-twisted cord, such as 11, 55 with the molding-strip 10. The body of the hanger-hook is formed of tubular material, which is bent into form after the insertion through the material forming the hook-body of an end portion of the wire cord 11. The 60 hook may be formed with a curved limb a on its upper end, that at its extremity is flattened transversely, so that said flattened end a' may seat in the groove 10^b of the molding-strip, which will prevent side swaying motion 65 of the cord 11 and of a picture-frame that may be hung therefrom. The hook may also be curved, so as to dispose its lower end close to the surface of the wall A, as shown at 12 in Fig. 2, or when it is desired to hold the cord 70 11 away from the wall the body of the hook may be bent, as shown at 12^a in Fig. 1. When the hook-body is designed to prevent a close approach of the cord 11 to the wall A, the curvature of the hook-nose may with advantage 75 be more open and the hook-limb be shorter, as shown at a² in Fig. 1, and in this construction of the hook an offset bend b may be formed in the body, which will afford a depending straight limb below the offset, said 80 limb being suitably spaced from the wall by the gravity of a picture-frame pendent therefrom.

The cord 11 is held in the tubular hook by the bended form of the latter and also by the 85 flattening of the upper end of the hook-body to produce the widened nose a' thereon, an additional means for preventing the hook from slipping off of the cord 11 consisting in turning the edge of the lower end on the hook-body inwardly, as at c, as shown in Fig. 3, thus bedding the thin edge of the hook-body into the wire cord. To connect with said frame the remaining ends of the pair of hanging-cords 11 required for suspension of the 90 frame from the molding-strip 10, I have provided a novel attachment. (Represented in Figs. 5 to 9, inclusive.)

In Fig. 5 the attachment is in the form of a tubular clip-band 13, from which projects 100

at a right angle a screw 13^a, the screw being at the lower end of the clip-band. In use the lower end of a cord, such as 11, is passed downward through the tubular clip-band 13 5 and out of the lower end of the passage therethrough, said passage d being turned away from the screw member 13^a. After insertion of the cord through the lower end d' of the passage d the lower and upper edges of said 10 passage may be bent toward the cord by any suitable means, so as to bind thereon, and thus firmly secure the attachment upon the cord. When two cords are employed for the suspension of a heavy picture or mirror frame 15 from the molding-strip 10, these similar cords each have one of the improved hooks secured upon one end and one of the novel screw attachments 13 13^a affixed upon the opposite end, and the latter mentioned fixtures are 20 then connected by means of the screws 13^a with the side portions of a picture-frame or the like, whereupon the hooks on the cords may be placed upon the molding-strip 10 for suspension of the frame, as is clearly shown, 25 for one hook in Fig. 10.

In Fig. 6 the attachment is similar to that shown in Fig. 5, with the exception that at one side of the tubular clip-band 14 a clamping-flange 14^a is formed; but a screw 14^b is projected laterally from the clip-band for insertion into a frame, as described for the screw 13^a. In connecting the device shown in Fig. 6 with a picture-frame-supporting cord 11 the lower end of such a cord is inserted downward through the tubular band 14, then out of the lower end thereof, an end portion thus withdrawn from the lower end of the clip-band 14 being bent upward, so as to lie in the concavity of the clamping-flange. After 35 the end portion of the cord is located in the tubular formation 14 and flange 14^a these parts may be clamped upon the cord 11 by a suitable implement, so as to firmly attach them to the cord.

40 The cord attachment shown in Fig. 7 is essentially the same in construction as that shown in Fig. 5, with the exception that the tubular clip-band 15 is longitudinally slotted, as at e, which permits the clip-band to be 45 clamped upon a wire cord 11 at the ends of said clip-band and also along the edges of the slots e, which will increase the clamping ef-

fect of the clip-band 15, a screw 15^a being projected laterally from the lower end of the slotted clip-band.

55

In Figs. 8 and 9 the tubular clip-band 16 is similar to the clip-band 13 and may be secured upon an end portion of a wire cord 11, as already described; but instead of a screw a split shank 16^a projects at a right angle 60 from the tubular member 16, as represented in Fig. 8, the two parts of said split shank when bent so as to aline with each other, as shown in Fig. 9, affording convenient means for engagement with an ordinary cardboard 65 frame.

75

Having thus described my invention, I claim as new and desire to secure by Letters Patent—

1. A picture-frame hanger, comprising a 70 flexible connection, a hook held on one end of the flexible connection, and a screw having a tubular clip-band disposed at an angle to the screw and receiving the other end of said flexible connection.

2. In a device of the character described, a means for attaching one end of a hanging-cord upon a frame, comprising a tubular clip-band through which the cord at one end is inserted and clamped by compression of the clip-band, 80 and an angularly-projecting member on one end of the tubular clip-band adapted for attachment to a frame.

75

3. In a device of the character described, the tubular hook adapted to hold an inserted 85 flexible connection, by bending the hook member at one end of the tubular material forming the body of the hook, after insertion of the flexible connection therein and also forming an offset bend in the hook-body between 90 its ends.

4. In a device of the character described, the cord attachment to engage a frame, comprising a tubular clip-band slotted lengthwise, open at its lower end, and provided with a 95 screw member disposed at right angles to the slotted clip-band.

80

In testimony whereof I have signed my name to this specification in the presence of two subscribing witnesses.

EMMET L. SMITH.
